UNITED STATES PATENT OFFICE.

JOSEPH D. CRONAN, OF PORTLAND, OREGON.

DESIGN FOR A NOVELTY DOLL.

50,934.

Specification for Design. Patented June 19, 1917.

Application filed April 15, 1916. Serial No. 91,493. Term of patent 7 years.

To all whom it may concern:

Be it known that I, JOSEPH D. CRONAN, a citizen of the United States, residing at Portland, in the county of Multnomah and State of Oregon, have invented a new, original, and ornamental Design for a Novelty Doll, of which the following is a specification, reference being had to the accompanying drawing, forming part thereof.

Fig. 2, a side view, and
Fig. 3, a rear view of a novelty doll, showing my new design.

I claim:
The ornamental design for a novelty doll, as shown.

JOSEPH D. CRONAN.

Witnesses:

A. M. MALLORY,
S. A. LAURANCE.
